UNITED STATES PATENT OFFICE.

LOUIS FERRETTE, OF PARIS, FRANCE.

CLOSING AND REGULATING COCK FOR ALL LIQUIDS AND GASES.

Application filed May 4, 1926, Serial No 106,772, and in France June 13, 1925.

My invention relates to a closing and regulating cock for all liquids and gases and at all pressures or vacuums, in which the output is stopped or regulated by operating a button 5 and by the action of a diaphragm upon a ball which serves to open or close the inlet for the gases or liquids.

Due to the disposition and the combination of the said parts, the use of a stuffing box is dispensed with, and the said cock does not comprise a third connection with the atmosphere such as occurs in devices for the insertion of the barrel or the needle of the usual cock.

15 The appended drawings show by way of example an embodiment of the invention.

Fig. 1 is a general vertical section of the cock, and

20 Fig. 2 is a corresponding front view, with the cover removed.

Fig. 3 is a fragmentary sectional view of a slight modification.

As shown in the drawing, the said cock comprises a cylindrical body 1, consisting of 25 brass, which is closed on the front side and forms on the front face a cup 2 with screw-threaded walls. The said body is pierced at the centre in order to form a central flange or cup 3 and a passage 4 which communicates 30 with a tapped orifice disposed at a right-angle thereto for the admission of the gas or liquid. The cup 2 of said body communicates through a passage 6 with a tapped orifice for the discharge of the gas or liquid.

35 The body is closed by a screwthreaded cover 7 which is screwed upon the cup 2. Said cover has a cylindrical portion 8 which is pierced at its centre with a tapped hole and has at the rear face a semispherical recess.

40 Upon the rear face of the said cover is mounted a tinned brass diaphragm 9 which is secured by soldering and is suitably shaped at its centre by the stamping process so as to fit into the semispherical recess of the said cover, and also to fit upon a ball 10 serving as a valve for which the seating is formed by the outer end of the passage 4. A packing ring 11 of fibre, lead or like material is placed 45 between the cover 7 and the end of the cup 2 so that the cover will have a fluidtight mounting upon the body of the cock.

50 The diaphragm 9 has concentric corrugations of the proper shape which are formed by the stamping process, whereby it is made elastic as well as rigid.

A screwthreaded tube 12, carrying a milled

knob 13, is screwed into the cylindrical part 8 of the cover 7 and it forms a recess co-operating with a step bearing 14 which is loosely engaged in the said tube. The head of 60 the said bearing makes contact with the diaphragm 9, and its other end makes contact with a steel button 15 which abuts against the inner face of the knob 13 adjacent the inner end of the tube 12.

65 The apparatus is completed by a coupling member 16 which is mounted on the inlet for the gas or liquid, and by a second coupling member 17 which is screwed within the outlet orifice.

70 In the modified form of the invention shown in Fig. 3, the gas or liquid inlet 16' extends through the rear wall of the device into direct communication with the conduit 4', the latter being straight instead of angular as in Fig. 1.

75 It will be noted from the foregoing that by operating the milled button 13 in the direction to screw the tube 12 into the portion 8 of the cover 7, the step bearing 14—through the 80 medium of the button 15—will drive out the diaphragm 9 which will make contact with the valve ball 10, so that the ball will be pressed upon its seat. The cock will now be in the closed position.

85 When the milled head 13 is turned in the other direction, the diaphragm 9 due to its elasticity will resume its initial form and will again enter the recess in the cover 7, driving back the step-bearing 14 and the button 15. 90 The valve ball 10 which is freed from the pressure of the diaphragm 9 and is subjected to the pressure of the gas or liquid contained in the conduit 4, will be raised from its seat, this giving passage to the liquid or gas, 95 which thus enters the cup 2 of the body 1 and is discharged through the passage 6 and thence through the outlet.

100 The discharge can be easily regulated by turning the head 13 in the unscrewing direction for an increased discharge, or in the other direction for a decreased discharge by moving the valve ball 10 from or towards its seat.

105 The device hereinbefore described is given solely by way of example, and the forms of the apparatus the details of construction, the accessories, material and dimensions may vary according to circumstances without departing from the principle of the invention. 110

I claim:

1. A closing and regulating cock, compris-

ing a body having an angular fluid passage therethrough with fluid inlet and outlet means communicating with said passage, a valve seat intermediate the ends of said passage, a valve movable on and off said seat, a flexible diaphragm adjacent the valve, a cover for retaining the diaphragm in position said cover having a recess opposite the valve seat, a tube adjustable in said cover, a bearing movable in said tube and means in said tube for moving said bearing into engagement with the diaphragm.

2. A closing and regulating cock for all liquids, which comprises a cylindrical body, a fluid inlet passage formed radially in the said body and having a right-angled central part, the front side of said body being recessed so as to form a cup, a central flange in said cup open at its outer end and which communicates with said right-angled central part of the passage, a fluid outlet passage which is formed radially in said cylindrical

body and separated by a wall from the fluid inlet passage and which communicates with the said cup by a right-angled passage, a closing ball disposed in the central flange of the cup, a screw threaded cover having a semispherical recess and screwed upon the front side of the said body, means affording a fluid-tight connection between the cover and said body comprising a concentrically corrugated diaphragm which is held at the periphery against the inner face of the cover and is adapted to fit upon the said cup, said cover having an axial aperture, a hollow screw co-operating with the wall of said aperture, means for actuating the said screw, and a step-bearing disposed in the aperture of the said screw and bearing against the said diaphragm.

Signed at Paris in the county of Seine and State of France this 12th day of March A. D. 1926.

LOUIS FERRETTE.
